UNITED STATES PATENT OFFICE.

GEORGE E. LOWMAN, OF VIRGINIA CITY, MONTANA.

SCABBARD.

SPECIFICATION forming part of Letters Patent No. 660,302, dated October 23, 1900.

Application filed July 19, 1900. Serial No. 24,212. (No model.)

To all whom it may concern:

Be it known that I, GEORGE E. LOWMAN, a citizen of the United States, residing at Virginia City, in the county of Madison and State 5 of Montana, have invented new and useful Improvements in Scabbards, of which the following is a specification.

My invention relates to bayonet-scabbards; and the object of the same is to provide simple 10 and efficient means whereby the interior walls of the scabbard may be kept clean and dry in order that the bayonet may be prevented from being rusted and may be kept bright and clean in all kinds of weather.

15 In the ordinary bayonet-scabbard no provision is made for keeping the inside of the scabbard clean. In fact, the construction of the ordinary scabbard is such that it would be extremely difficult, if not impossible, to provide 20 efficient means for getting into the inside of the scabbard to clean it out. This defect in bayonet-scabbards is entirely overcome by my invention.

In the accompanying drawings, which form 25 a part of this specification, Figure 1 is a perspective view of a scabbard made in accordance with my invention. Fig. 2 is a perspective view of the scabbard open. Fig. 3 is a detail perspective of one of the catches for holding the scabbard closed.

Like numerals indicate like parts wherever they occur in the different views.

In said drawings the numerals 1 and 2 designate the two parts or sections of my scabbard. These two sections may be made of sheet metal or other material and are shown as curved in cross-section to provide space 35 between said two parts for the bayonet. The section 1 may have a beaded edge 3, and the section 2 has a bead 4 at its upper end. The two sections are hinged together by the hinge-joint 5, which may be of any suitable construction. On the outer surface of section 1 a belt-hook 6 is provided, by means of 40 which the scabbard is supported from a waist-belt. Curved flat springs 7 are secured by rivets 8 longitudinally within the two sections, and these two springs come into con-

tact and exert some tension when the scabbard is closed. Two transverse springs 9 50 are secured by rivets 10 at different points within the sections 1 and 2, the upper spring being for the purpose of throwing the sections apart when the latches are released. The latches 11 may be formed of strips of spring 55 sheet metal, having the curled catch portions 12 and the finger-pieces 13. The latches are adapted to pass through the apertures 14 in the section 2 of the scabbard, and when the two parts are brought together the latches 60 catch the margins of the apertures to hold the sections together, and to open the scabbard the finger-pieces 13 are pressed together. The upper spring 9 then throws the sections apart and permits access to the inner surface 65 of the scabbard for cleaning.

From the foregoing it will be obvious that my scabbard may be kept clean and bright upon the inside and that the bayonet will not come in contact with a wet or rusty surface, and but little time will be required in 70 keeping it bright and clean.

Having thus fully described my invention, what I claim is—

1. A bayonet-scabbard made in sections, 75 hinged together, and latches for holding the sections closed, substantially as described.

2. A bayonet-scabbard comprising two sections hinged together, latches for holding the sections closed, and springs for separating 80 the sections when the latches are released, substantially as described.

3. A scabbard comprising two sheet-metal sections hinged together, latches for holding the sections together, springs for throwing 85 the sections apart, and a supporting-hook for engagement with a belt, substantially as described.

In testimony whereof I have hereunto set my hand in presence of two subscribing witnesses.

GEORGE E. LOWMAN.
